UNITED STATES PATENT OFFICE.

CHARLES L. BUCKINGHAM, OF NEW YORK, AND EMIL GERMANN, OF BROOKLYN, NEW YORK;
SAID GERMANN ASSIGNOR TO SAID BUCKINGHAM.

APPARATUS FOR PERFORATING FILLETS OF PAPER FOR THE AUTOMATIC TRANSMISSION OF MESSAGES, &c.

No. 880,275.

Specification of Letters Patent.

Patented Feb. 25, 1908.

Application filed October 25, 1902. Serial No. 128,696.

To all whom it may concern:

Be it known that we, CHARLES L. BUCKINGHAM, of the city, county, and State of New York, and EMIL GERMANN, of Brooklyn, 5 Kings county, and State of New York, citizens of the United States of America, have made a new and useful improvement in apparatus for perforating fillets of paper for the automatic transmission of messages or 10 for such other purposes as perforated tape of this general character may be applicable.

The present invention is an improvement upon that class of perforating machines shown in United States Letters Patent of 15 Buckingham and Germann, No. 659,433, October 9, 1900, in which is a punch head through which passes a fillet or band of paper, the latter being first prepared with a central row of perforations, wherein apertures on each side of said central row are 20 next perforated. In this machine is also employed a feed wheel having peripheral pins which mesh with the central holes of the tape both as it approaches the punch head and emerges therefrom. By this means, the tape is held under tension on either side of the punch head, and thus it is 25 that the outer holes may be punched in exact cross-alinement with those of the central row.

The difficulty which the present invention is intended to obviate lies in the fact that the central row of holes may not be straight and that the holes perforated near the margins of 30 the tape may not, therefore, be equidistant from those of the central row, thus rendering the tape defective as a means for message transmission, particularly when employed with the Wheatstone transmitter. To overcome 35 this difficulty, a means has been employed for holding the tape as it passes through the punch head in such precise relation to the punches that the central row of holes shall be exactly midway between those 40 of the marginal rows.

Referring to the accompanying drawings, Figure 1 represents a top view of the feed wheel, punch head and message fillet. Fig. 2 is a side view showing the fillet and one of 45 the two die plates of the punch head between which the fillet of paper passes while being perforated. Fig. 3 is a perspective view of a small toothed guide wheel meshing

with the central apertures of the paper whereby the latter is held in such position, 55 as it enters the punch head, as to bring the central perforations midway between the two rows of punches. Fig. 4 shows a fillet of paper provided with central holes and such marginal perforations as are employed in telegraphic characters. 60

Referring to Fig. 1, *a* is a feed wheel which is provided with radial teeth; while *k* is a fillet of paper, having central perforations, which in the operation of the machine first 65 passes over one side of said wheel, thence around the punch head to an idler or guide roller *b*, thence over toothed guide roller *c* through the punch-head slot between the two 70 housings *e*, *f*, over guide roller *d*, and thence to wheel *a*, with whose teeth the central holes, *l*, of the tape again engage.

In the ordinary construction of this machine, the feed wheel rotates upon a vertical axis and the fillet *k* is in a vertical plane at 75 all positions of its movement from and to the feed wheel, over the guide rollers, and through the punch head; although, obviously, the feed wheel might rotate on a horizontal axis, in which case the slot of the punch head 80 should be in a horizontal rather than in a vertical plane.

The tape *k* for use in a Wheatstone transmitter is ordinarily provided with holes, *l*, 85 ten to the inch, along its length, and, obviously, these should be along the longitudinal center of the paper fillet, and in a straight line. If the central holes are in a straight line, and the tape is supported at the right height at the back or ingress end of the punch head, the teeth of wheel *a*, which rotate in a plane midway between the two sets of punches, must draw the central holes of the fillet through the punch head in a line 90 midway between the punches *g* and *h*. The punches *g* are driven inward toward the tape and through the same to perforate the lower holes, *m*, (Fig. 4) while punches *h* are driven in the opposite direction, or toward the observer looking at Fig. 1, to punch the holes, 95 *n*, near the upper margin.

Fig. 2 shows one of the die plates of the punch head and the relation to the central holes of the apertures therein through which the punches work. As seen, the upper 100 apertures *h'* serve as guides for punches *h*, which,

in the operation of perforating, are thrust through the paper and into corresponding apertures of the die plate on the opposite side of the paper; the punches *g*, however, are guided by apertures in the plate nearest the observer (Fig. 1), and are driven through the paper into apertures *g'*, Fig. 2.

Owing to the size of the feed wheel *a* and the necessity for an adjustable guide roller *d*, it is not feasible for the fillet *k* to come into mesh with the teeth of the feed wheel *a* until said fillet is at a considerable distance from the punch head. From this fact, if the central holes were not in a perfectly straight line, or if the tape were held too high or too low as it entered the punch head, the central perforations would not be equidistant between the marginal holes *m* and *n*; Fig. 4.

By employing a small guide roller *c*, as shown in Figs. 1 and 3, having spur teeth *i* rotating in a plane between punches *g*, *h*, the tape may be held in such position that even if the central row of holes were not straight the discrepancy would be only slight. But to this end, the wheel *c* should be journaled as near the punches as possible.

An adjustable guide roller *d* is also used whereby the tape may be given a greater or less length between the punch head and the feed wheel. By this means, the central holes are accurately brought into transverse alinement with the punches and with apertures *g'*, *h'* of the punch head.

Wheel *c* might be journaled entirely within the punch head; or two such spur wheels might be employed, one at each end of the punch head; but a sufficient degree of accuracy may be attained by one such wheel, as shown in Figs. 1 and 2.

What we claim and desire to secure by Letters Patent is—

1. In a perforating machine for preparing telegraphic messages or for perforating a fillet of paper for other purposes, the combination of a feed wheel having peripheral teeth, a band of paper provided with a central row of apertures, a punch head, through which said paper passes, provided with punches for perforating apertures in said fillet on either side at a definite distance from said central row of perforations, and a guide wheel *c*, having spur teeth, which is in close proximity to the punches of the punch head, for holding the central holes of said fillet in proper relation to the punches, as and for the purpose set forth.

2. In a perforating machine, the combination of a feed wheel *a*, having radial teeth, a fillet of paper *k* provided with a central row of perforations, a punch head provided with a central vertical aperture through which said fillet of paper passes, two ranges of punches, *g*, *h*, for perforating marginal apertures, and a toothed guide wheel *c*, in close proximity to the punches of the punch head whereby the central row of perforations is carried through said punch head in a line midway between said ranges of punches, as and for the purpose set forth.

In testimony whereof we have signed our names to this specification in the presence of two subscribing witnesses.

CHARLES L. BUCKINGHAM.
EMIL GERMANN.
